HIGH SPEED CONTROL SYSTEM FOR LINE CASTING MACHINES

Joseph J. Ackell, Amityville, N. Y., assignor to Dow Jones & Company, Inc., New York, N. Y., a corporation of Delaware

Application July 15, 1955, Serial No. 522,209

26 Claims. (Cl. 199—18)

This invention relates to an automatic control system for line casting machines. The control is effected in accordance with perforations in a punched tape which is advanced step by step through an analyzer. More particularly, the invention relates to various new features and combinations embodied in a system of the general character disclosed in the Joseph J. Ackell Patents Nos. 2,704,595 and 2,704,596, granted on March 22, 1955.

A primary object of the invention has been to provide a control system of the character indicated which is adapted for use in connection with any existing line casting machine, such as the types sold under the trade name "Linotype" and "Intertype" and which brings about the operation of the machine at the maximum overall speed permitted by the inherent limitations of the machine.

It has been observed that the limiting factor, in efforts to speed up the operation of a line casting machine, is the time required to bring about the successive release of two or more matrices of the same character. So long as different characters, regular spaces, and the like follow successively in a given line, the speed of release of the necessary matrices may be quite rapid. However, when the same type of matrix is to be released in two successive positions, an extra amount of time is required to insure proper operation of the machine. This is because the release of a second matrix of the same type as the preceding one cannot be effected until the particular releasing means involved has been restored to its normal position. On the other hand, the release of a matrix of different character may be initiated before the previously operated releasing means has been so restored.

Accordingly, a special feature of the present invention is the provision of a control system which brings about operation of the line casting machine normally at the maximum safe speed permitted when the successive matrices to be released are of different character. A special time delay is introduced into the control system whenever two or more successive matrices to be released are of the same type, as in printing "cc" for example. Toward this end, the preferred form of the new system is arranged to double the normal time cycle of the machine whenever a repetition of the preceding character is called for.

Another feature of the invention is the inclusion of similar automatic means in the system for allowing extra time whenever a particular form of matrix, such as a "space band" matrix, is released in the line casting machine. This is to allow adequate time for the proper assembly of the space band in the line, more time being required for this than for the assembly of other types of matrices.

The improved system incorporates many of the features of the above mentioned Ackell Patent 2,704,596, such as a control cam unit having a constantly rotating shaft the speed of rotation of which determines the speed at which successive matrices are released in the line casting machine. This shaft, in accordance with the present invention, is rotated at a higher speed than was pos-

2

sible in the system disclosed in said patent and conforms with the maximum safe speed for the release of successive matrices of different types. When the same character is to be repeated in immediate succession in a given line, the preferred control circuits are such that two revolutions of the constantly rotating shaft are required for the release and proper assembly of the matrix for the repeated character. It has been observed that, in general, such repeated characters constitute only between 10 and 20% of the total number of characters to be printed, so that it is possible to effect a substantial overall increase in the speed of operation of the line casting machine through the use of the present invention.

To enable the introduction of a time delay, whenever the same character is to be repeated, the control system includes two sets of relays which are successively energized in accordance with the code perforations in the tape. The first set of relays is energized directly in accordance with the perforations in the tape as they are being analyzed. The second set of relays is controlled in accordance with the setting of the first set of relays, and the matrix releasing circuits are energized in accordance with the setting of the relays of the second set. Certain control cams provided on the constantly revolving shaft bring about an appropriate timing of the various controls whereby the readings determined by the analyzer pins of the tape box are transmitted to the first set of relays, the setting of the latter is then transferred to the second set of relays, the matrix releasing circuits are controlled by the second set of relays, and a comparison is made between the settings of the two sets of relays. The arrangement is such that whenever the settings of the two sets of relays are compared, as described above, and it is found that their settings coincide, the circuits for releasing a matrix under control of the second set of relays are opened after releasing the first matrix of the repeated character and will not be operated during the next cycle of the timing shaft. However, the second set of relays is released and then reset in accordance with the setting of the first set. During the next cycle of operation of the timing shaft the circuits through the matrix releasing solenoids will be open so that no matrix will be released. The setting of the second set of relays will be held throughout this cycle and into the next. During such next cycle the normal operation of the system will be resumed and at the proper time a matrix will be released in accordance with the held-over setting of the second set of relays. It will be understood that this is an over simplified explanation of the operation of the system and that other controls are brought into play as will appear more clearly from the detailed description to be given hereinafter.

In the new system two special relays are provided to bring about the automatic control of the various devices in the manner explained above. One of these will be designated a "control relay" and the other a "compare relay." The control relay remains energized so long as no repeat characters are encountered in the matter to be set up on the line casting machine, except under circumstances, to be explained, in which the second set of relays mentioned above is set-up in accordance with certain specific code designations in the tape. However, when the comparing circuits for the two sets of relays above mentioned show that their settings coincide because of the repetition of the same character, the compare relay is energized and this serves to release the control relay. This brings about the introduction of an extra cycle of the constantly rotating timing shaft which provides the extra time required for the release of like matrices in the line casting machine.

During a single revolution of the constantly rotating timing shaft the following sequence of operations or steps

takes place. The analyzer pins of the tape box determine the information in a particular line across the tape. If the control relay is energized at this time, the information is transferred to the first set of relays. The tape is then advanced to the next line of perforations; at the same time, a matrix is released in accordance with the setting of the second set of relays, i. e. the information stored in the second set of relays controls the release of a matrix in the line casting machine. The settings of the two sets of relays are compared and the second set of relays is then released and quickly reset to correspond with the existing setting of the first set of relays. If upon comparison of the setting of the two sets of relays they are found to differ, no change in the circuits of the system is brought about and the same sequence of operations takes place on the next revolution of the shaft. On the other hand, if at the time of comparing the settings of the two relays they are found to coincide the compare relay is energized and this, as explained, brings about the release of the control relay. Nevertheless, the second set of relays will be released and then re-established in accordance with the then setting of the first set of relays. However, the release of the control relay will cause the first set of relays to be released and to remain blank, the second set of relays holding its setting, during the next cycle of the timing shaft. No movement will be imparted to the tape on this cycle of the timing shaft and no matrix will be released in accordance with the setting of the second set of relays. The compare relay will be released toward the end of the cycle and the previous setting of the second set of relays will continue to be held. From this point of the original cycle of operations will be repeated, the control relay becoming energized at the beginning of the new cycle.

It should be understood that when a line has been fully composed at the line casting machine, an elevator operating signal which has been sensed by the analyzer pins of the tape box and transferred in due course to the second set of relays will, at the appropriate time in the cycle, bring about the operation of the elevator in accordance with the disclosure of the above mentioned Ackell patent 2,704,596. This involves a time delay mechanism which provides adequate time for the various operations that must take place, such as the jogging of the line of matrices, the lifting thereof to the transfer position, and the transfer thereof to the casting position and finally the restoration of the parts to the normal position in which a new line may be assembled. During this interval the continuously operating timing shaft will be rendered ineffective so that the tape feeding and other operations explained above will not take place.

A further object of the invention has been to simplify the construction of various devices employed in the system and to reduce to a minimum the number of moving parts in the system. Thus a simplified form of tape box, with tape feeding and analyzing devices, has been incorporated in the system. The new tape box has fewer parts and is more compact than tape boxes heretofore employed. So also the number of relay switch members has been reduced, taking into account the increased number of functions requiring relays for their control. This has been achieved by the employment of a substantial number of rectifiers which predetermine a given path for the current even though several circuits may be completed by the operation of the relays. As a result of the simplification of the devices employed and the reduction of the number of moving parts, the servicing requirements of the equipment have been materially reduced.

Moreover, various devices have been assembled into separate units for the purpose of facilitating service and repair of the system. So also, provision is made for the elimination or by-passing of the two sets of relays whose settings are compared and for the direct control from the tape box of a group of relays which select the particular key operating solenoid which is to be energized during

any cycle of the system. This enables continued operation of the line casting machine in the event that some difficulty develops in the two sets of relays whose settings are compared during a matrix releasing cycle. It should be understood, however, that when the direct control is provided from the tape box to the key operating solenoids the overall speed of the machine must be reduced to insure adequate time for the release of repeat characters. In the printing of matter having an unusually high percentage of repeats the overall speed of the machine may be greater under this arrangement of the control system than when the two sets of relays to be compared are active.

Other objects, features, and advantages of the invention will appear from the detailed description of an illustrative embodiment of the invention which will now be given in conjunction with the accompanying drawings, in which:

Figs. 1a, 1b, 1c, 1d, 1e and 1f collectively constitute a wiring diagram of the new system, various control elements being indicated schematically;

Fig. 2 is a top plan view of the improved tape box;

Fig. 3 is a front elevational view of the tape box with a portion of the enclosing housing removed;

Fig. 4 is an end elevational view of the tape box with a portion of the housing and other elements removed;

Fig. 5 is a detail view of a switch within the tape box arranged to be operated when the tape becomes tight;

Fig. 6 is a detail view illustrating a detent arrangement for insuring proper step by step movement of the tape advancing means within the tape box;

Fig. 7 is a plan view of certain parts of a cam shaft assembly or unit having a constantly driven timing shaft and various circuit control cams;

Fig. 8 is a side elevational view of the cam shaft unit, 35 with a cover plate removed;

Fig. 9 is an elevational view of certain parts within the cam shaft unit, as seen from the right in Fig. 8;

Fig. 10 is a plan view of the cam shaft unit;

Fig. 11 is a side elevational view of the unit taken 40 from the opposite side from that shown in Fig. 8, certain parts being removed or shown only in part;

Fig. 12 is an end view of the cam shaft unit as seen from the right in Fig. 11, with a portion of the housing broken away to show certain control cams and switches 45 therein;

Fig. 13 is a vertical sectional view through a portion of the cam shaft assembly showing additional control cams and switches operated thereby;

Fig. 14 is a diagrammatic view illustrating the timing 50 of various functions in the operation of the control system;

Fig. 15 is a plan view of a section of tape having code perforations representing the word "accord";

Fig. 16 is a chart illustrating the succession of events 55 incident to the release of matrices in the line casting machine to form the word "accord";

Fig. 17 is a side elevational view of a portion of the keyboard solenoid unit forming part of the control system and a relay unit detachably connected therewith;

Fig. 18 is a view similar to Fig. 17 with certain parts 60 broken away and shown in section for illustration of devices within the units;

Fig. 19 is an elevational view, with parts broken away, of a hood-like connecting element serving to attach the 65 relay unit to the solenoid unit;

Fig. 20 is a view similar to Fig. 18 with the separable parts of the assembly shown in spaced relation;

Fig. 21 is a plan view of a portion of the solenoid 70 and relay units with parts broken away and with a portion of the connecting element shown in section along the line 21—21 of Fig. 18;

Fig. 22 is a detail view, in front elevation, of a contact element strip embodied in the solenoid unit;

Fig. 23 is a detail view in vertical section showing

two contact carrying plates of the solenoid unit and the relay unit in spaced relation;

Fig. 24 is a vertical sectional view along the line 24—24 of Fig. 20, with the relay unit elevated slightly in relation to the solenoid unit preparatory to assembly; and

Fig. 25 is a horizontal sectional view taken along the line 25—25 of Fig. 20 showing a bracket element attached to the solenoid unit.

Referring now to Figs. 1a to 1f inclusive, the various electrical devices and circuits and certain related control elements will now be described. To form the complete circuit diagram Figs. 1a, 1b, and 1c should be placed end to end, with their major length horizontal, and Figs. 1d, 1e, and 1f should be similarly placed and positioned directly beneath Figs. 1a, 1b, and 1c, respectively. In Fig. 1d the box indicated by the broken outline 10 represents switches and other devices applied to the line casting machine for the control of various operations.

Key operating solenoids, of the character disclosed in the prior Ackell patents mentioned above, are indicated by the small rectangles 11 extending across Figs. 1a to 1c inclusive adjacent the top thereof. A group of relays 12, shown divided into two groups for better illustration of the circuits controlled thereby, serves to control a plurality of switch arms 12b to 12y inclusive. These switch arms are shown aligned across Figs. 1a—1c with the respective relays of the group 12 which serve to operate them. It will be understood that these arms are normally shifted toward the left into engagement with the contacts on the left side thereof. Whenever a relay in the group 12 is energized, the arms related to that relay will be shifted toward the right. The arrangement is such that a single circuit will be completed through the selected solenoid of the group 11 to effect the operation of the selected key at an appropriate time in the cycle of operation of the system.

A cam shaft unit 13, indicated schematically by a broken line in Fig. 1e, is suitably mounted on the frame of the line casting machine. This cam shaft unit receives power from any suitable source, such as an electric motor which serves to drive continuously a shaft 14 carrying a plurality of cams I, II, III, IV, and V. These cams are formed of suitable insulating material and cooperate with various switches to bring about the desired timing of the operation of certain devices embodied in the control system. Shaft 14, in accordance with the invention, is operated at a relatively high speed which is suitably selected in accordance with the characteristics of the line casting machine to which the invention is applied. It is such that the time interval allotted by a single revolution of the shaft is sufficient to enable the selection and release of matrices of successively different character in the line casting machine. In a typical set-up of the system the shaft has been rotated at a speed of 540 R. P. M. Any suitable means may be provided for adjusting the speed of rotation of the shaft. The cam shaft unit also includes a shaft 15 which is given a single revolution at periodic intervals, i. e., upon completion of the selection of the matrices to constitute a single line. Shaft 15 carries three cams, one of which is designated "Control Relay Opening" and controls the operation of a relay hereinabove referred to as the control relay. It normally holds a switch closed in the circuit of the control relay but this switch is opened at the commencement of rotation of shaft 15 and is closed again upon the completion of a single revolution of this shaft. Also secured to shaft 15 is a cam, designated "Elevator Drop," for controlling the return of the elevator of the line casting machine. A third cam on the shaft 15, designated "Jogger," controls a relay for bringing about the jogging of the matrices assembled in the elevator prior to the lifting of the latter. A disc carrying a crank pin is also secured to the shaft 15 for mechanically operating the elevator. The operation of shaft 15 is similar to that of the shaft 334 in Ackell Patent 2,704,596. When re-

leased for rotation by an elevator lifting signal, predetermined by the punched tape, it will be turned through a small angle and then be held by another detent until a mechanical timing device brings about the release of the second detent. Shaft 15 will then rotate through the remainder of 180° from its initial position to lift the elevator and it will be held in that position until a detent is released under the control of the cross delivery mechanism of the line casting machine. When released for further rotation under control of the cross delivery mechanism the shaft will return to its initial position and will then cause the control relay to be reenergized and render the cams on the shaft 14 effective to control the assembly of another line of matrices. Shaft 15 is driven from the shaft 14 through suitable gearing and a slip clutch. The gearing is such that shaft 15 is driven at a slower speed than the shaft 14 to insure smooth operation of the elevator mechanism.

A tape box 16 (Fig. 1f) is provided to feed a punched tape step by step to present successive lines of perforation in the tape in the path of analyzer pins designated 0, 1, 2, 3, 4, and 5. The tape box preferably provided in accordance with the invention is of an improved, simplified form and will be described in detail hereinafter. It will be sufficient to explain here that appropriate circuits in the system are arranged to energize a tape feeding magnet in the tape box whenever the tape is to be advanced to its next position and in the course of advancing the tape the analyzer pins will be retracted from the openings previously entered in the tape and permitted to enter the next line of openings. The correlation between the perforations in the tape and the characters or functions predetermined by the different number and arrangement of the perforations across the tape are in accordance with the code system disclosed in the Paulding et al. application Serial No. 433,982, filed June 2, 1954, now Patent No. 2,788,886, granted April 16, 1957.

Each of the analyzer pins of the tape box is in circuit with one of a group of relays 17 which may be designated group "A." At an appropriate time in the cycle of operation of the system, selected relays of this group may be energized, in accordance with the perforations in the tape, to operate a plurality of switch arms. A second set of relays 18, which may be designated group "B," corresponding in number and arrangement with the relays in group "A" is arranged to be energized at an appropriate time in the cycle of the system to set-up appropriate switch arms corresponding with the switch arms of group "A." Appropriate circuits are provided in the system for holding the settings of the relays of groups "A" and "B" over different portions of a cycle of the system and, while the relays of the two sets are being held, an appropriate circuit is closed for bringing about a comparison of the settings of the relays of the two groups. If the settings are found to be similar, which indicates a repeat in the matter to be set up in the line casting machine, a relay hereinbefore described as a compare relay is energized. This releases the control relay and in effect provides a second revolution of the shaft 14 for completion of the assembly of the repeated character in the line casting machine.

The control of the two groups of relays "A" and "B" is such that group "A" is first energized and held in accordance with the perforations in the tape. This setting is then compared with that in group "B" which is being held from its previous setting. Group "A" is then released and quickly reset in accordance with the next line of perforations in the tape. Group "B," at an appropriate time in the cycle, delivers its setting to the relays of group 12 which, as previously explained, serve to select the particular key operating solenoid to be operated during a cycle of the system.

The sequence of events in the control by the cams on shaft 14 over the two groups of relays "A" and "B" and also the control and compare relays described above is

depicted in the diagram of Fig. 14. A cycle is indicated as being divided into four quadrants I, II, III, and IV and time is considered to run in a counterclockwise direction from the point indicated as $t=0$. It will be noted that at this time whatever setting had been transferred to the relays of group "B" is being held. Moreover, the subsequent setting of the "A" group relays is being held. Also the control relay is being energized, released, or held, depending on the condition of various circuits. Toward the end of the first quadrant the group "A" relays will be released as indicated by "gap" and they will then be reset in accordance with the new line of perforations in the tape. This is indicated by the notation "transfer A" in quadrant II. During this interval the relays of group "B" will be held in accordance with their previous setting and the compare relay will remain either energized or deenergized in accordance with its last setting, as will also the control relay. The relays of group 12 will be energized upon the energizing of the relays of group "B" and will be held to correspond with the setting of the latter so long as the group "B" relays remain energized. During the third quadrant the tape feed of the tape box will be operated and the setting on the group "B" relays, acting through the relays of group 12, will bring about operation of the appropriate key operating solenoid. During this same quadrant, simultaneously with the operation of the selected matrix releasing solenoid, the setting of the two groups of relays "A" and "B" will be compared to determine whether the compare relay should be energized because a repeat character is indicated by the similar setting of the relays of groups "A" and "B." Toward the end of quadrant III the group "B" relays are released and then reset during quadrant IV to correspond with the then setting of the group "A" relays which are being held throughout quadrants III and IV.

The sequence of events in the control of the line casting machine by the tape is illustrated further in Figs. 15 and 16. In Fig. 15 there is shown a small section of a punched tape 19 having tape feeding openings 20 and successive lines 21 of coded control perforations extending across the tape. The number and position of the perforations across the tape determine the character to be set up or other function to be performed. The perforations illustrated represent the word "accord." As this section of tape advances through the analyzing zone of the tape box the events tabulated in Fig. 16 will take place. Each timing cycle referred to represents one revolution of the shaft 14. During the first cycle in which the "a" perforations in the tape are analyzed the control relay will be energized and the relays of group "A" will then be set in accordance with the letter "a" and this setting will be held for nearly a complete revolution of the timing shaft. Shortly after the group "A" relays have been energized the tape will be advanced to position the next line of perforations in the path of the analyzer pins. The relays of group "B" will be in their normal or blank position and therefore, at the time when a matrix would normally be released none is released. The circuits which serve to compare the setting of the relays in groups "A" and "B" are next rendered effective but since the settings of the two groups are different, the compare relay will remain at rest, i. e. deenergized. At the conclusion of the first timing cycle the relays of the "B" group will be set in accordance with the setting of the "A" group. As the second timing cycle begins the line of perforations in the tape representing the first "c" will be in the analyzing position and since the control relay is still energized the circuits completed by the analyzer pins will set up relays in group "A" representing the letter "c." The tape is then advanced to present the next line of perforations identified with the second "c" at the analyzing position. Since the setting of the "B" group of relays corresponds with the letter "a" a matrix bearing that letter will be released in the line casting machine. Upon the subse-

quent comparison of the settings of the relays of groups "A" and "B," it will be found that they differ so that the compare relay will remain deenergized. Following this the relays of group "B" will receive the same setting as group "A" and thus represent the letter "c." At the beginning of the third timing cycle the perforations in the tape representing the second "c" will be in the path of the analyzer pins and since the control relay is still energized the relays of group "A" will be released and then reset to represent the second "c." The tape is then advanced to the perforations corresponding with the letter "o." At this time the relays of group "B" are set for the letter "c" and a matrix for the first "c" in the word "accord" will be released. Upon subsequent comparison of the settings of the relays of groups "A" and "B" they will be found to coincide and this will energize the compare relay and in turn deenergize the control relay. As the third cycle is completed the relays of group "B" will be released and reset to correspond with the second "c" in the assumed word. At the beginning of the fourth timing cycle the perforations in the tape will represent the letter "o" but since the control relay has been released the relays of group "A" will be released and remain in released condition and not assume the setting for the letter "o." No movement will be imparted to the tape. While the "B" group of relays remains set for the second "c" of the word no matrix will be released because of the release of the control relay. The compare relay will be released at the proper time in the cycle but the relays of group "B" will be held, by a special circuit to be explained, to carry over to the next cycle the setting for the second "c." At the commencement of the fifth timing cycle the tape will still have the "o" line of perforations in the analyzing zone, and the control relay being energized will cause the group "A" relays to be set in accordance with "o." The tape will then be advanced to the line representing "r" and the relays of group "B," being set to represent the second "c," will cause the release of the second "c" matrix. As the comparison circuits are set into operation the settings of the two sets of relays will be found to differ so that the compare relay will remain released. At the conclusion of this cycle the group "B" relays will be released and reset to correspond with "o." The remaining cycles follow the pattern of the first and second, so that at the conclusion of the eighth cycle six matrices for the word "accord" will have been released and since the tape has no perforations in line with the analyzing pins throughout this cycle, the relays of both groups "A" and "B" will all be released.

With the foregoing general explanation as to the functioning of the improved control system, the electrical circuits and devices embodied in the new system will now be described in general detail. Figs. 1a-1f, inclusive, together constitute the circuit diagram of the system. To form the complete diagram for the system Figs. 1a, 1b, and 1c should be placed end to end and directly beneath these Figs. 1d, 1e, and 1f should be placed end to end. As shown in Fig. 1e, there is provided a plug or junction box 22 arranged to receive power from a suitable direct current power source. A power switch 23 (Fig. 1b) is provided for throwing the system into and out of operation as desired, while a further switch 24, provided at a convenient location, may be operated to throw the line casting machine out of operation whenever any difficulty arises. It will be understood that when the system is to be put into operation, switches 23 and 24 will be closed and power will also be supplied to the motor which drives the timing shaft 14 of the cam assembly unit. The first thing to occur at this time is the energizing of the control relay 25 (Fig. 1b). Current for energizing this relay is derived from the power source through the plug 22. A positive line 26 from the latter is connected into a line 27 which passes through the number 1 contacts of a Jones plug and socket 28 and then upwardly to the switch 23.

From the latter it extends through line 29 over toward the right and then downwardly to a line 30 (Fig. 1f) which continues the circuit through contacts 7 of a Jones plug and socket 31. From the latter the circuit continues through the line 32 and through switch 33, which is normally closed and only opened when the punched tape being fed through the tape box becomes too tight. From the switch 33 the circuit extends through contacts 8 of the plug and socket 31 and through a line 34 to the switch 24, and then downwardly through a line 35, through contacts 6 of the plug and socket 28, then through line 36 to and through contacts 10 of a Jones plug and socket 37. From the latter the circuit continues through the line 38, through switch 39, line 40, switch 41, line 42, contacts 17 of plug and socket 37, downwardly through line 43, through switch 44, then line 45 through contact 18 of plug 37, down through line 46, through switch 47, then through line 48 and contact 3 of plug 37 to line 49 which extends over to a switch 50 normally held closed by the control relay cam on the shaft 15. The latter, it will be recalled is rotated only in response to an elevator lifting signal in the punched tape. From switch 50 the circuit continues through line 51 to a switch 52, which is closed by the action of the segmental portion of cam V on the shaft 14 at an appropriate time in the cycle of operation of the latter. When switch 52 is closed the circuit continues through line 53, contacts 5 of plug and socket 28, line 54 and line 55 to a switch arm 56a of a relay 56 which is the compare relay of the system. This, as has been explained, is normally deenergized so that the arm 56a will be in its lefthand position in engagement with the contact at the upper end of the line 55. From arm 56a the circuit continues through line 57 to and through the coil of control relay 25, to the line 58 connected with the negative side of the power switch 23, downwardly through line 59, contacts 2 of plug and socket 28, to line 60 which is connected with the negative side of the plug 22. Thus it will be seen that upon the closing of the switches 23 and 24 and the starting of the timing shaft 14, the relay 25 will be energized as soon as the cam V operates the switch 52.

A holding circuit is provided for maintaining the relay 25 in energized condition until the circuit is broken at some point, as by the release of the elevator operating shaft 15 or by the call for a repeated character by the punched tape or the call for release of a particular type of matrix, or the like. This holding circuit may be traced from the positive line 29 through a line 61, branch line 62, and switch 63 which is actuated by cam IV. From switch 63 the circuit extends through line 64, contacts 17 of plug 28, and a switch arm 65 to a line 66 connected with one side of the relay 25, the opposite side of this relay being connected as previously indicated through line 58 with the negative side of the power source. It should be noted in this connection that the arm 65 of the relay 25 will be engaged with the contact at the end of line 66 by virtue of the previous energization of the relay 25. Also, it should be noted that the camming portions of cams IV and V are such that they overlap in their action to maintain the relay 25 energized continuously until the circuit is broken at some other point as explained. Moreover, the arrangement is such that the relay 25 can be deenergized only during an interval in which the switch 63 is open, since the holding circuit for relay 25 is opened only at this switch once the relay is energized. While the switch 52 is at this time closed, the circuit through the relay 25 will be broken at the arm 56a of the compare relay 56 when this is energized.

Upon energization of the control relay 25, circuits may be completed through one or more of the relays 17 (group "A") in accordance with the location of perforations in the region of the tape being analyzed by the analyzer pins of the tape box 16. The analyzer pins are designated 0, 1, 2, 3, 4, and 5 and these are connected respectively through contacts 6, 1, 2, 3, 4, and 5 of the plugs

31. Contacts 6 of these plugs are connected through a line 67 with one side of a relay 17a in the group 17. The opposite side of this relay is connected through line 68 with the line 58 which, as previously indicated, is connected with the negative side of the current source. The circuit is completed to the positive side of the current source from the opposite side of the analyzer pin 0 in the tape box through line 69, contacts 10 of plugs 31, line 70, contacts 8 of plugs 28, switch 71 cooperating with cam II on the shaft 14, then through line 72, contacts 16 of plugs 28, a contact 73 which is at this time engaged by an arm 74 that has been shifted toward the right through the operation of the relay 25, then through line 75 to a positive line 76 connected into the power switch 23. 15 Thus, assuming that a perforation is present in the tape in the 0 position the relay 17a will be energized when the cam II closes the switch 71.

In a similar way, circuits will be completed through the relays 17b, c, d, e, and f of group "A," whenever the 20 associated pins of the pin box are aligned with perforations in the portion of the tape being analyzed at a particular time. The connections from pins 1, 2, 3, 4, and 5 to the respective relays of group "A" are through lines 77, 25 78, 79, 80 and 81 (Fig. 1f). Thus, all of those relays of group "A" will be energized which are in circuit with analyzer pins aligned with perforations in the tape. The 30 circuits for relays connected with pins that are being held down by the tape are broken at a point within the tape box.

30. Those relays 17 (group "A") which are energized in accordance with the perforations in the tape are held energized by a circuit extending from the positive side of the power switch 23 through line 29, line 61, contacts 14 of plugs 28, switch 82 held closed during a large portion 35 of the rotation of shaft 14 by cam III, then through line 83, contacts 18 of plugs 28, line 84 and those switch arms of the group 85, 86, 87, 88, 89, and 90 which have been operated by the energizing of selected ones of the 40 relays 17. The arms so operated are drawn downwardly by the energized relays into engagement with the adjacent contacts, so that the circuit is then completed through the coils of the energized relays to the line 68 which, as previously noted, is connected into the negative line 58.

It should be noted in connection with the foregoing 45 that the cams II and III are so formed that at the end of the holding action of cam III a slight gap is provided before cam II becomes effective to energize a new series of relays of group 17. Once such a new series of relays has been energized, through the action of cam II, these 50 will be held energized by cam III for most of the balance of a complete revolution of shaft 14, because of the overlapping relationship of the trailing end of cam II and the forward end of cam III.

The energizing circuits for the relays 18 (group "B") 55 will now be described. These circuits start at the positive side of the power switch 23, extend through lines 76 and 75 to the switch arm 74 of relay 25, which at this time is shifted toward the right into engagement with the contact 73. From here the circuit continues downwardly 60 through contacts 16 of plugs 28, then through line 72, line 91, and switch 92 to a line 93. The latter is connected, through contacts 7 of the plugs 28, with line 94 extending to switch arms 95, 96, 97, 98, 99, and 100. The switch arms of those groups which are related to 65 energized relays of group 17 are drawn downwardly into engagement with the contacts indicated beneath them and thus close circuits through one or more of the lines 101, 102, 103, 104, 105, and 106 to one or more of the relays 18a to 18f, inclusive, of group 18. The opposite sides of the coils of relays 18a to 18f, inclusive, are connected into the negative line 58. Thus, whenever the 70 switch 92 is operated by cam II certain relays in group 18 will be energized, i. e. those which correspond with the ones then energized in group 17. Whichever relays of group 18 are thus energized will be held by circuits

extending from the positive side of the power switch 23, through line 29, line 61, switch 107, operated by cam III, line 108, line 109, and whichever of a group of switch arms 110, 111, 112, 113, 114 and 115 have been operated by the relays of group 18. These arms will have been drawn upwardly, into engagement with the contacts shown, to deliver the current to the coils of the energized relays and the circuits will be completed through those coils to the negative line 58.

As explained in relation to relays 17, the cams II and III are so related that the holding of the circuit by cam III will cease just prior to the next operation of the switch 92 by the cam II to energize another series of relays in group 18. However, in the case of relays 18 (group "B") it is sometimes desired to hold these in accordance with their previous setting, in spite of the gap in the action of cams II and III. This, as explained in relation to Fig. 16, is whenever the compare relay has been energized, as in response to the repetition of the same perforations in the tape. The holding circuit for the selected relays 18 (group "B") at this time extends from the positive side of the power switch 23 through line 76, line 75, switch arm 74 which has been restored to its lefthand position by deenergization of the control relay 25 upon the operation of the compare relay 56, then through line 108 to line 109 which is directly connected with the switch arms 110-115 inclusive to hold the energized relays of group "B." It will be understood that so long as the control relay 25 remains energized the alternate circuit just described will not come into play and the relays of group "B" will be released momentarily by virtue of the gap in the action of cams II and III and will then be reset in accordance with the then existing setting of the relays of group "A."

The relays 18 (group "B") are interconnected with corresponding relays of group 12 so that whenever one of the relays of group 18 is energized a corresponding relay in group 12 will be energized. This, as previously explained, will cause the shifting of various switch arms of the group 12b to 12y inclusive to complete a circuit through one of the key actuating solenoids 11 at an appropriate time in the cycle.

The circuits interconnecting relays 18 with relays 12 are as follows: Assuming that relay 18f is energized a switch arm 117 will be swung into engagement with the contact shown above it. Similar switch arms 118, 119, 120, 121, 122 will be swung upwardly (Fig. 1c) whenever the corresponding relays 18e, d, c, b, and a are energized. Switch arm 117 closes a circuit from positive line 76 through line 76a, the switch arm 117, line 123, and a branch line 124 to relay 12-5 of group 12. The opposite side of this relay is connected into line 125 which is common to all of the relays of group 12 and which is in turn connected by line 126 into negative line 58. Switch arm 118 when actuated completes a circuit to a line 127 which is connected with relay 12-4 of group 12, while switch arm 119 when actuated completes a circuit to line 128 and through relay 12-3 of group 12. Switch arm 120 when actuated completes a circuit to line 129 and through relay 12-2 of group 12. Switch arm 121 when actuated completes a circuit to line 130 and through relay 12-1 of group 12, while switch arm 122 when actuated completes a circuit to line 13 and line 131a through relay 12-0 of group 12.

At an appropriate time in the cycle of the system a matrix corresponding with the then existing setting of the relays of group 12 will be released. This circuit may be traced from the positive side of power switch 23 through line 29 and a fuse 29a to a switch arm 132 shown at the top of Fig. 1b. From this point the circuit may be completed along any one of a variety of different paths through the various switch arms 12b to 12y inclusive, depending upon the position of the arm 132 and the positions of the switch arms controlled by the relays of group 12. From the switch arm 12y the circuit con-

tinues through line 133 and a branch line 133a, contacts 4 of plugs 28 to lines 134, 135, 136, and 137, contacts 3 of plugs 28, line 138, to a line 139 and thence through switch arms 140 and 141, arranged in parallel, to contacts connected with negative line 58. Switch arms 140 and 141 will be shifted toward the right into engagement with their contacts so long as the control relay 25 is energized. By providing the two switches in parallel the current load carried by each is cut in two.

As has been previously indicated, the system is so constructed that during each cycle of rotation of shaft 14, in the unit 13, a comparison is made between the settings of the relays in the groups 17 and 18 (groups "A" and "B"). If the previous setting of the group 17, which is now being stored in group 18, is found to coincide with the new setting of group 17, thus indicating the appearance of a repeated character in the tape, the compare relay 56 is energized. The circuit for accomplishing this will now be traced. Starting with the positive side of the power switch 23, the circuit extends through line 29 then downwardly through line 61, contacts 14 of plugs 28, over and down to switch 142 controlled by cam V on shaft 14. From this switch the circuit extends upwardly through line 143, contacts 20 of plugs 28, and over to a switch arm 144 controlled by relay 18f. If this relay is energized the arm will engage the contact at the end of line 145 and the circuit will be carried to the contact at the lower end of this line. If relay 17f is also energized a switch arm 146 will be shifted downwardly into engagement with the contact at the lower end of line 145. On the other hand, if neither relay 18f nor 17f is energized, the circuit from arm 144 to arm 146 will be completed through the line 147. In the event that one of these two relays is energized and the other is not, the circuit will be broken at the arm 146. Assuming that the circuit is completed to the arm 146, this is connected with an arm 148 controlled by the relay 17e. If the latter is energized the arm will be shifted downwardly to engage a contact at the lower end of line 149 and if the corresponding relay 18e is also energized, the circuit will be carried to an arm 150 controlled by the latter relay. On the other hand, if both of the relays 17e and 18e are deenergized the circuit will be completed to the line 150 through line 151. Should the setting of the two relays not coincide, the circuit will be broken at the arm 150. Again assuming that the circuit is completed to arm 150 this is connected to an arm 152 controlled by the relay 18d. If the latter is energized the arm will engage the contact shown above it and the circuit will extend through line 153 to an arm 154 controlled by the relay 17d, providing the latter is also energized. If neither relay 18d nor 17d is energized the circuit will be carried from arm 152 to arm 154 through line 155. Should the settings of the two relays not coincide the circuit will be broken at the arm 154. If the circuit is completed to arm 154, it is continued to an arm 156 of the relay 17c which, if energized, will engage the contact beneath it and extend the circuit through line 157 to arm 158 which will be shifted upwardly if relay 18c is also energized. In the event that both relays 17c and 18c are deenergized, the circuit from 156 to 158 will pass through line 159. On the other hand, if the settings of the relays do not coincide the circuit will be broken at the arm 158. If the circuit is completed to arm 158 it will continue to arm 160 of relay 18b and if the latter is energized it will extend through line 161 to arm 162 of relay 17b. If neither relay 18b nor relay 17b is energized the circuit from arm 160 to arm 160 to arm 162 extends through line 163. As before, if the settings of the two relays do not coincide the circuit will be broken at the arm 162. The latter is connected with an arm 164 of relay 17a which if energized will draw the arm downwardly into engagement with the contact at the lower end of line 165. The upper

end of this line will complete the circuit to an arm 166 of relay 18a if the latter is also energized. In the event that neither relay 17a nor 13a is energized, the circuit from arm 164 will extend through line 167 to arm 166. As before, if the settings of the two relays do not coincide the circuit will be broken at the arm 166.

Now assuming that the settings of the two sets of relays have coincided throughout, the circuit will be completed to the arm 166 and from the latter will continue through line 168 and branch line 169 to one end of the coil of relay 56. The opposite end of this coil is connected with the negative line 58. Thus the compare relay will be energized. It is held energized by a circuit extending from the negative line 58, through the coil of relay 56, then through an arm 170 of relay 56, which will at this time be shifted toward the right, thence through line 171, contacts 19 of plugs 28, to switch 172 controlled by cam IV. From this switch the circuit is completed to the positive side of the source through line 173, line 61, contacts 14 of plugs 28 and line 29.

So long as the compare relay 56 is energized, it will shift and hold the arm 56a toward the right thus breaking the circuit to the control relay 25 at this point. Cams V and IV are such that once the relay 56 is energized it will be held energized until a condition arises in which the circuit through switch 172 is open and the circuit through 142 is closed. This means that it is held for nearly a complete revolution of the shaft 14 when it is once energized. It will not remain energized for more than a complete revolution even though the effective portions of the cams IV and V overlap at their two ends since, as shown in the chart of Fig. 16, all of the relays 17 (group "A") will be deenergized or become "blank" upon the release of the control relay 25. This is because the circuit to and through the relays of group "A" extends through arm 74 and contact 73 and the circuit will be broken here whenever the relay 25 is deenergized. Accordingly, at the time a comparison is next called for, by cam V, of the settings of the relays of groups "A" and "B," group "A" will be blank while group "B" will still carry a setting corresponding to the second one of the repeated characters which brought about the operation of the compare relay 56. In the event that the tape calls for the same character three or more times in succession, as in the printing of a number having a series of zeros, the compare relay will be operated again during the cycle in which the third 0 is set up in the relays of group "A" and this is compared with the retained 0 of group "B."

Referring further to Fig. 16, it will be noted that during the fourth timing cycle, in which the control relay is released, no matrix will be released. This is due to the fact that the circuit through any one of the key operating solenoids 11, as hereinabove traced, extends from the switch 136 through lines 137, 138, and 139 to switch arms 140 and 141 which upon release of relay 25 will be disengaged from their contacts and thus will not complete the circuit to the negative line 58.

Normally during each cycle of the system, the tape feeding mechanism of the tape box will be operated. This is with the exception, previously noted, in which the control relay has been released by the energizing of the compare relay. The circuit to the magnet in the tape box, which retracts the analyzer pins and imparts the feed movement to the tape, starts from the positive side of the power switch and extends through line 29, down through line 30, contacts 7 of plugs 31, line 32 through the coil 174 of the tape feed magnet, then through line 175, contacts 9 of plugs 31 to line 133, through contacts 4 of plugs 28, lines 134 and 135 to switch 136, upon closing of the latter by cam I, and back to the negative side through line 137, contacts 3 of plugs 28, lines 138 and 139, and switch arms 140, 141 to line 58. It will be noted that this circuit requires the energization

of control relay 25, since otherwise the circuit will be broken between the arms 140, 141 and their associated contacts. Accordingly, when the compare relay has been energized, with subsequent release of control relay 25, the tape feeding magnet will not be operated.

In the tracing of circuits through the key operating solenoids reference has been made to a switch arm 132. This is connected with a relay 176 (Fig. 1c) which is the "shift" relay of the system that is energized whenever upper case letters are to be printed. Energizing of relay 176 is brought about through a line of perforations in the tape in the 1, 2, 4, and 5 positions. It should be borne in mind that the perforations in the tape are identified with positions 0, 1, 2, 3, 4, and 5 and the code relation of different combinations of perforations to the key operating solenoids or to the other functions to be performed are as disclosed in the pending application of Paulding et al., Serial No. 433,982.

Now when the relays 12 are set in accordance with perforations in the 1, 2, 4, 5 positions of the tape, the relay 176 will be energized through the following circuit. From the positive side of power switch 23 the circuit extends through line 29 to the switch arm 132, which may be in either of its possible positions. The arm itself does not enter into the circuit to be described, but the circuit extends from the arm through branch line 177 to the switch arm 12d which, at this time, is in its lefthand position, then through line 178 to switch arm 12i, which is in its righthand position, then through line 179 to one end of the coil of relay 176. From the opposite end of the latter the circuit continues through line 180 to a line 181 and down to switch arm 12q, which is at this time in its righthand position, then through line 182 to switch arm 12v which is in its lefthand position, then through line 183 to switch arm 12x which is in its righthand position, and through line 184 to switch arm 12y which is in its righthand position. From the latter the circuit is completed through line 133, branch line 133a, lines 134 and 135, switch 136, lines 137, 138, and 139 to switch arms 140, 141 to the negative line 58.

When the shift relay 176 is energized it will be held until an unshift signal is indicated by a line of perforations in the tape. The holding circuit for relay 176 extends from positive line 29 through a switch arm 185 which is shifted toward the left, when relay 176 is energized, into engagement with a contact at the end of a line 186 connected with the left end of the coil of relay 176. The opposite end of this coil is connected with the negative side of the line through switch arm 187, which is drawn into engagement with the contact shown opposite it by the action of relay 176, then through line 188, switch arm 189 which is normally in its lefthand position, then through line 190 to line 125 down to line 126 which, as previously explained, is connected with the negative line 58.

Release of the shift relay 176 is brought about through the operation of an unshift relay 191 which serves to withdraw the arm 189 from the contact at the end of line 188. Operation of unshift relay 191 is brought about through a line of perforations in the tape in the 1, 2, 3, 4, and 5 positions. When the relays 12 are energized in accordance with this line of perforations the circuit through relay 189 will be completed from the positive line 29 through line 177, switch arm 12d which will be shifted to its lefthand position, line 178, switch arm 12i, which will be shifted to its righthand position, line 179 to the coil of relay 191, then through lines 192 and 193 to switch arm 12v which will be in its righthand position, through line 194 to switch arm 12v which will be in its righthand position, through line 183 to switch 12x which is in its righthand position, and then through line 184 to switch 12y which is in its righthand position, to line 133 and down to switch 136 and back up to arms 140, 141 and to the negative line 58. The system will

remain in the "unshift" condition until a new "shift" signal is transmitted to relays 12 and under their control to relay 176.

The line casting machine is provided with upper rail and lower rail mechanism for positioning each matrix either in an upper rail position in which its bold face type will be cast or in a lower rail position in which its normal face type will be cast. The circuits of the present system for controlling the determination of whether the upper rail or the lower rail will be effective in positioning given matrices are similar to those described above in relation to the shift and unshift relays. Thus an upper rail relay 195 and a lower rail relay 196 are provided and the operation of each of these is controlled by a particular arrangement of perforations in a line across the tape. To render the upper rail relay effective the holes in the tape should be in the 0, 1, 4, and 5 positions, while to render the lower rail effective the holes should be in the 0, 1, 2, 4, and 5 positions. Normally the lower rail is effective and is rendered ineffective upon the operation of the upper rail relay. The latter is held in its energized condition after it is once energized until the lower rail relay is operated at which time the parts are restored to their normal position.

Assuming that an upper rail signal has been transferred to the relays of group 12, the relays 12-0, 12-1, 12-4 and 12-5 will be energized. A circuit will then be completed through relay 195 from the positive line 29, through line 177, arm 12d which will be in its shifted righthand position, line 197, arm 12j, which is now in its righthand position, line 198 and line 199 to and through the coil of relay 195. From the latter the circuit is completed to the negative side through line 200 over to line 201, to switch arm 12o which is in its righthand position, then through line 202 to switch arm 12u which is in its lefthand position, to line 203, arm 12x which is in its lefthand position, through line 184 to arm 12y which is in its righthand position, and from the latter through line 133, switch 136, and lines 138, 139, arms 140, 141 to the negative line 58. When so energized, the relay 195 is held by a circuit extending from the positive line 76 to a line 76b connected at its lower end with a switch arm 204 which is, at this time, shifted toward the left by the energized relay 195. From arm 204 the circuit continues to the lower end of the coil 195 and from the upper end of the latter to a line 205, to a switch arm 205a which is shifted toward the left at this time by the operation of relay 195. From switch arm 205a the circuit extends through line 206 to switch arm 207, which is in its normal lefthand position, then through line 208 to line 209, which extends downwardly and over toward the left to the number 12 contacts of plugs 28, then through line 210 to contacts 9 of plugs 37 and down through line 211 through contact number 3 of plug 212, then through a line 213 to a switch 214, which is normally in the off position shown, to a line 215, through a microswitch 216 which normally has its arm in the upper position, through a line 217 to the negative line 218 which is connected through contacts 1 of plugs 37 and through line 219 with the negative side of the plug 22.

So long as relay 195 is energized the upper rail in the line casting machine is effective. The circuit for controlling the upper rail mechanism in the machine extends from the negative line 209 (traced from the source as above) up to a switch arm 220 of relay 195 which, at this time, is shifted toward the left by operation of relay 195, and the circuit continues downwardly through line 221 over to the left of the diagram through contacts 11 of plug 28, then through line 222 and contacts 7 of plugs 37 to line 223 and through contacts 1 of plugs 212, to a rotary solenoid 224 of the type sold under the trade name "Lexed," which operates the upper rail mechanism. From the solenoid 224 the circuit extends to positive line 225 which extends upwardly through con-

tacts 8 of plugs 37 to a line 226 connected with the positive side of plug 22.

When the upper rail is to be released and the machine restored to the lower rail condition, the relay 196 is energized by the adjustment of the relays of group 12 to correspond with holes in the 0, 1, 2, 4, 5 positions in the tape. The circuit extends from positive line 29 to line 177, arm 12d which is in its righthand position, line 197, arm 12j which is in its righthand position, line 198, line 227 through the coil of relay 196, line 228 to line 181, through the latter to arm 12q which is in its righthand position, to arm 12v which is in its lefthand position, to arm 12x in its righthand position, and thence through line 184 to arm 12y which is in its righthand position. From the latter the current to the negative side extends through the switch 136, as explained above. Upon operation of relay 196 the arm 207 will be shifted toward the right to break the holding circuit for relay 195 and this will bring about release of the arms 204, 205a, and 220 so that the circuit through the rotary solenoid 224 will also be broken and the rail mechanism of the line casting machine will be restored to render the lower rail effective.

In the new control system, provision is made for the operation of the compare relay 56 to introduce a time delay in the operation of the line casting machine whenever a space band matrix is released. This is to allow sufficient time for the assembly of the space band in the group of matrices in the elevator before any other matrices are released or any other operation of the line casting machine is initiated under control of the tape. For this purpose an alternate circuit through the compare relay 56 is created whenever the relays of group 12 are set in accordance with the code designation for a space band. This simply calls for the energizing of the relay 12-3 identified with a number 3 perforation in the tape.

The circuit calling for release of a space band matrix may be traced as follows: from the line 29 to switch arm 132 and from the latter through line 177, arm 12d, line 178, arm 12i, line 230, over to the space band solenoid near the left end of the circuit diagram. From this the circuit continues through line 231, line 232, arm 12-1, line 233, arm 12s, which will have been shifted toward the right by the energizing of relay 12-3, line 234, arm 12w, line 235 to arm 12y, which, as previously noted, is connected through the switch 136, at an appropriate time in the cycle, with the negative line 58. This part of the circuit extends through arms 140, 141 which are shifted toward the right so long as the control relay 25 remains energized.

Parallel with the circuit through the space band solenoid is another circuit formed by a line 236 (Fig. 1a) to the coil of a relay 237 and a line 238 to the opposite side of the space band solenoid. Energizing of relay 237 by this parallel circuit will set up a holding circuit which extends from the positive line 76 through switch arm 239, which will be shifted to the left by the operation of relay 237, then through the coil of the relay, through line 240, contact 241, switch arm 242 which will now be shifted toward the left, line 243 to line 139, arms 140, 141 to the negative line 58. This holding circuit will be effective until the control relay 25 is released.

Operation of relay 237 brings about operation of the compare relay 56 through a circuit which extends from positive line 76 through a switch arm 244 which is shifted toward the left by operation of relay 237, then through line 245 to the line 169 connected with the upper end of the coil of relay 56. The lower end of this coil is connected with the negative line 58. Operation of the compare relay 56 will, as before explained, break the circuit through the control relay 25 at the arm 56a which will now be drawn toward the right. Release of the control relay 25 will, as stated above, break the holding circuit for the relay 237.

Provision is also made in the new system for maintain-

ing the control relay 25 in energized condition even though the compare relay is operated in response to corresponding settings of the relays of groups "A" and "B" identified with a tape feed or "rub out" code designation in the tape. The code designation for a tape feed is the absence of any perforations across the line, while the code designation for "rub out" is a perforation in each of the 6 positions across the tape.

As explained above, the release of the control relay comes about through the breaking of the holding circuit for the latter between the line 55 and switch arm 56a. A parallel circuit serving to connect these is provided whenever the compare relay is actuated as a result of having either all or none of the relays of groups "A" and "B" energized. In fact the parallel circuit identified with tape feed, i. e. no perforations, becomes effective whenever the group "B" set of relays are all open. Similarly the parallel circuit becomes effective when all of the relays of group "A" are energized in response to a "rub out" signal in the tape.

Tracing the parallel circuit created by the tape feed signal, this extends from the lower end of line 55 toward the right through line 246 to an arm 247 forming part of relay 18f. When this is not energized arm 247 is in its lower position and in engagement with the contact at the end of line 248 which continues the circuit to arm 249 of relay 18e, which is in its lower position, then through line 250 to arm 251 of relay 18d, which is engaged with the contact at the end of a line 252 which, in turn, is connected with the arm 253 of relay 18c. The latter through line 254 is connected with arm 255 of relay 18b which engages at this time the contact at the end of line 256, the opposite end of which normally engages the arm 257 of relay 18a. From this arm the circuit extends through line 258 upwardly and over toward the left to the lower end of switch arm 56a, thus completing the parallel circuit.

In a similar manner a parallel circuit, which connects line 55 with arm 56a, is completed through switch arms of the relays of group "A" when all of these relays are energized in response to a "rub out" signal in the tape. The connection from line 246 extends, at this time, through branch line 259 to arm 260 of relay 17f which is interconnected with arm 261 of relay 17e in turn connected with arm 262 of relay 17d and so on to and through arms 263, 264 and 265 of relays 17c, 17b, and 17a, respectively. From arm 265 the parallel circuit is again completed through the line 258. It will be understood that when a tape feed or "rub out" signal is involved, there is no need to delay the operation of the system since no matrix is released. Therefore the circuits just described are desirable to maintain the normal high speed of operation of the system.

In the event that it is desired to eliminate the relays of groups "A" and "B" from the control system, because of the need for repair or some other purpose, these relays may be thrown out of operation by disconnecting the Jones plug 31 from the cooperating socket in the tape box 16 and plugging in instead the Jones plug 266 shown near the top of Fig. 1c. It will be noted from the circuits indicated that the relays of group 12 will, in this event, be connected directly with the tape box and the system may operate in the manner disclosed in the Ackell Patent No. 2,704,596. It will be understood that when this is done, the speed of operation of the timing shaft 14 in the cam shaft unit 13 will need to be reduced to conform with the time required for the successive release of like matrices.

As indicated on the circuit diagram (Figs. 1a-1f inclusive) a large number of rectifiers, preferably of the selenium type, are employed in the system. One such rectifier 267 is provided beneath each of the key operating solenoids. A large number of others indicated by the conventional symbol are provided at other points in the circuit. These rectifiers, which may be thought of

as stationary switches, and which if not provided would require the presence of a large number of additional relays involving moving parts, enable the completion of a single circuit, whereas in their absence a plurality of circuits would be completed under various conditions. A typical instance of this will be explained. Let us assume that the relays of group 12 are set for Z, this would involve the energizing of relays 12-1 and 12-5 and the release of the other relays of the group. Also the shift relay 176 would be energized. Upon operation of the switch 136 during rotation of the shaft 14 a circuit will be completed as follows: from positive line 29 through switch arm 132, line 268, arm 12c in its lefthand position to arm 12g which is shifted toward the right, then through line 269 to line 270, and from the latter through line 271, through the Z solenoid to line 272, and thence through line 273 to arm 12-o, line 202, arm 12-u, line 203, arm 12-x, line 184, arm 12-y and down through line 133 to the negative side of the line in the manner explained. If rectifiers were not provided beneath the several key operating solenoids parallel circuits from line 270 to line 272 would be completed through various other solenoids. One such parallel circuit would extend from line 269 through solenoid B, then up through solenoid B to line 274 then down through line 275 to and through the Z solenoid to the line 272. Thus with this single parallel circuit three additional matrices would be released if the rectifiers were not present and were not replaced by suitable relays. Other parallel circuits could be similarly traced which would result in release of additional matrices.

At numerous points in the circuits of the new system there is provided a contact protector which is indicated in Figs. 1a to 1f inclusive by a symbol representing a pair of opposed rectifiers with a plus sign. Such a contact protector serves substantially the same purpose as a condenser and resistance shunted across the portion of the surface to be protected. One of the double rectifier protectors is associated with each of the relays in the system, as indicated at 276 in relation to relay 17a of group "A." It is provided in a line shunted across the coil of the relay.

Upon the completion of assembly of a line of matrices in the elevator of the line casting machine provision is made in the new control system for bringing about the automatic lifting of the elevator and the operation of a cross delivery mechanism to transfer the assembled matrices to the line casting position. This operation is initiated by the punched tape which is provided with a perforation in the number 2 position whenever the elevator mechanism is to be operated. It will be understood that in the course of operation of the system this elevator lifting signal in the tape will be analyzed and during several cycles of the shaft 14 of the cam shaft assembly will be transmitted to the relays of group 12 so that relay 12-2 will be energized while the remaining relays of this group will be released. When cam I on shaft 14 now closes switch 136 certain circuits in the system will be energized to bring about release of the shaft 15 for a single revolution in several stages. At the same time the circuits controlled by the cams on shaft 14 will be rendered ineffective through the release of the control relay 25 and these circuits will remain ineffective until completion of the revolution of the shaft 15.

The circuit which is completed upon the closing of the switch 136 during the cycle in which only relay 12-2 of group 12 is energized will be traced from the plug 22. This circuit extends from the positive line 26 through line 27 to contact 1 of the lower plug 28, through line 277, and a fuse 278 to one side of the coil of a magnet 279. The opposite side of this coil is connected by a line 280 with contacts 9 of plugs 28 and the circuit continues upwardly to a switch arm 281 in the upper left corner of Fig. 1a. This switch arm, identified with relay 75 12-0, will be in its lefthand position as will also a switch

arm 282 identified with relay 12-5. The circuit thus continues through arm 282, line 283, arm 12-m which is in its lefthand position, line 284, arm 12-t which is in its lefthand position, line 285, arm 12-w which is in its righthand position, line 235 to switch arm 12-y which is in its lefthand position; from the latter the circuit is completed to the negative side of the line through the switch 136 in the manner previously explained.

Energizing a magnet 269 will withdraw a detent 286 from an arm 287 secured to the shaft 15 and permit the latter to rotate a slight distance. A mechanical time delay of the type disclosed in Ackell Patent No. 2,704,596 is associated with the cam shaft assembly to insure allowance of an adequate variable amount of time for the proper operation of the elevator and associated devices.

The initial movement of the shaft 15 will cause the control relay opening cam 288 on shaft 15 to open the switch 50 and thus release the control relay 25 and break the various circuits described above which are under control of the cams on shaft 14. Also the initial turning of shaft 15 will cause the cam 289, designated "jogger," to close a switch 290 to bring about operation of the jogging mechanism of the line casting machine. The circuit for this purpose extends from the positive line 277 through a branch line 291, having a fuse 291a therein, to and through the switch 290, then through line 292 to the number 5 contacts of plugs 37. From the latter line 293 continues the circuit to and through a rotary solenoid 294 which operates the jogger mechanism. The opposite side of this solenoid is connected by line 295 through contacts 4 of plugs 37 with negative line 219.

When the mechanical time delay mechanism releases the arm 287 from the second detent, not disclosed in the circuit diagram but disclosed in the Ackell patent mentioned and in Fig. 11 of the present application to be later described, the shaft 15 is permitted to complete its first half revolution at which time an arm 296 engages the detent 286. This results in the lifting of the elevator which is followed by the operation of the cross delivery mechanism. Completion of the revolution of shaft 15 is not brought about until the cross delivery mechanism is restored to its normal position and closes a switch 297, Fig. 1d. It should be noted that at the time this switch is closed a cam 298 on shaft 15 is holding a switch 299 closed since the shaft will have rotated 180° from the position indicated in Fig. 1e. A circuit will now be completed through the magnet 279 from the positive line 277 through the coil of the magnet, then through line 299a to the switch 299 and from the latter through line 300 to contacts 6 of plugs 37, down through the now closed switch 297 to the negative line 219 extending through contacts 1 of plugs 37. Energizing of magnet 279 will withdraw the detent 286 from the arm 296 and permit the shaft 15 to complete its revolution at which time the arm 287 will again be engaged with the detent 286. When the shaft 15 is restored to its normal position indicated in Fig. 1e, the cam 288 will again close the switch 50 and enable the cams on shaft 14 to complete the various circuits herein above described through the control relay 25, the tape box and other portions of the system. Thus the system is prepared for the assembly of another line of matrices in the elevator in the same manner as has been described.

Referring now to Figs. 2 to 6 inclusive, there is disclosed an improved form of tape box employed in the new system for advancing and analyzing the punched tape. Various parts are identified in these figures by the numbers applied to the portions thereof schematically shown in the circuit diagram of Figs. 1a to 1f inclusive. The box has a generally rectangular box-like frame 301 housing the operating parts. The electromagnet 174 is suitably supported within the frame and arranged to operate an armature 302 rockably mounted upon a pivot 303. Each time the magnet 174 is energized the arma-

ture will be rocked and its right portion or arm 304 will be moved downwardly against the action of springs 305 which normally hold the armature in the position shown in Fig. 3. Springs 305 are connected at their upper ends to studs 306 carried by the frame and at their lower ends to the right end of the arm 304. A pair of screws 307 threaded into the frame have their heads arranged to serve as stops for the upward movement of the armature. These screws may be adjusted to vary the position of their heads to suit the requirement of the device. Pivotally mounted on the arm 304 by means of a screw 308 is a pawl 309, the upper end of which is arranged to cooperate with the teeth of a ratchet 311. The pawl is drawn against the ratchet by means of a spring 310. Ratchet 311 is carried by a shaft 312 which is rotated step by step upon the operation of armature 302, 304. An adjustable eccentric stop element 313 is preferably provided to assist in guiding the pawl in its longitudinal movements. Adjacent the mid portion of the shaft 312 there is secured thereto a toothed wheel 314 arranged to cooperate with tape feeding holes provided centrally of the punched tape. Adjacent the right end of the shaft 312 (Fig. 4) there is mounted a toothed wheel 315 (Fig. 6) with which cooperates a detent 316 carried by an arm 317 pivoted by means of a screw 318 on a portion of the frame. Arm 317 is drawn upwardly by a spring 319 to hold the detent 316 yielding in one of the notches between the teeth of the wheel 315. As the pawl 309 engages and rotates the ratchet 311 the wheel 315 will cam the detent roller 316 downwardly and as the detent roller rides over the high point of the aligned tooth of wheel 315 the spring 319 will draw the arm sharply upwardly to complete the feeding movement of the shaft 312 and retain it in its new position.

A plurality of spring rod or wire conductor elements 320 are secured to the armature directly beneath its pivot 303 and these elements extend in cantilever fashion toward the right (Fig. 3). Adjacent their right ends they fit into openings in heads 321 carried by the lower ends of vertically disposed feeler pins 322. The springiness of the wires or rods 320 is such as to normally hold their outer ends in engagement with the under surface of a contact bar 323 carried by the arm 304 of the armature. As the armature is rocked, upon energizing of the magnet 174, the contact bar 323 will depress the rods 320 and draw the feeler pins 322 downwardly out of cooperation with the punched tape. When the armature is restored those feeler pins which are aligned with perforations will rise to their normal positions but those which find no perforations in the tape will be held downwardly by the latter so that the free ends of the related rods or wires 320 will be held out of engagement with the common contact bar 323. The latter, it should be noted, corresponds with the line 69 in Fig. 1f. Adjacent their upper ends the feeler pins 322 are slidably mounted in collars 324 which extend downwardly from the top 325 of the housing. The top 325 is provided with a recessed portion 326 through which the punched tape is advanced by the feed wheel 314. When the feeler pins 322 are in their uppermost positions the ends thereof pass through perforations in the tape to close related circuits between rods or wires 320 and the contact bar 323. It will be understood that a cable or group of wires within the tape box serves to connect the rods 320 and the common contact bar 323 each with a different contact of a Jones plug 320a. Through this plug the tape box is connected into the circuits disclosed in Figs. 1a-f, inclusive. A plate 327 extends across the tape box in the region of the feeler pins and is hingedly mounted at 328 on the frame of the box. This cover member is normally retained in the position shown in Fig. 4 by means of a latch 329 having a hook 330 cooperating with the edge of an opening through the top 325. When it is desired to insert a new tape or inspect the tape in the analyzing position because of some difficulty being encountered, the

latch 329 is rocked clockwise (Fig. 4) against the action of a spring 331 (Fig. 2) and the cover member 327 may then be swung upwardly about its pivot 328.

As explained in relation to the circuit diagram provision is made for stopping the operation of the system whenever the tape becomes too tight. For this purpose a stud 332 (Figs. 2 and 5) is rockably mounted in a wall of the tape box and carries an enlarged knurled head 333 by which it may be manually turned, whenever desired, to stop the operation of the system. Within the tape box the stud 332 carries a cam 334 having a laterally extending finger 335 adapted to cooperate with fixed stops 336 and 337 which determine the limits of angular movement of the stud. An L-shaped arm 338 has a portion projecting radially from the knurled head 333 and a transversely extending portion arranged to cooperate with the perforated tape as the latter advances to the analyzing position. The transverse portion of arm 338 normally rests upon the upper surface of the tape. If the latter becomes taut the arm 338 is lifted, thereby rocking the stud 332 in a clockwise direction (Fig. 5) and the cam 334 will then depress a spring arm 339. The latter carries a C-shaped spring element 340 the opposite end of which is connected with a spring arm 341. The arrangement is such that after a predetermined flexing of the spring 340 it will impart an upward movement to the spring arm 341 and this will separate a contact at the end of an arm 342 from a contact at the end of arm 341, thereby opening the switch. This switch is the one designated 33 in Fig. 1f. The arms 342 and 341 are connected by wires, not shown, with two contacts of the plug 320a (Fig. 2). When the switch is opened due to the tightness of the tape the circuit hereinabove described which energizes and holds the control relay 25 will be broken during the time that this circuit is normally closed by the action of cam V on the switch 52. Opening of the circuit through the control relay 25 will prevent the energizing of the key operating solenoids and will also prevent the energizing of the feed magnet 174.

Now turning to Figs. 7 to 13 inclusive, these illustrate some of the mechanical features of the cam shaft assembly 13 whose operation has been described in relation to the circuit diagram. This cam shaft assembly is similar in many respects to that disclosed in the Ackell Patent 2,704,596. However, it differs in certain respects due to the nature of the circuits which it must control. The cam shaft unit has a frame 344 and connected housing which encloses most of the devices forming a part of the assembly. The walls of the frame serve to support the shafts 14 and 15 described in relation to the circuit diagrams. Power is supplied to the unit through a pulley 14b (Fig. 7) outside of the enclosed housing and adapted to be connected by a belt with a suitable motor. The connections for driving the pulley and shaft are such that the speed of rotation of the shaft may be controlled to provide the desired timing of the system.

Within an enclosed portion 345 of the frame of the cam shaft assembly there is provided a suitable connection between the shafts 14 and 15. These connections, which are not fully shown, are of the character disclosed in Fig. 2 of the above mentioned Ackell Patent 2,704,596. The arrangement is such that shaft 15 is driven through a friction clutch which permits slippage when the shaft 15 is held against rotation. However, when the shaft is released it is driven at an angular speed slower than that of the shaft 14. Release of the shaft 15 for rotation is accomplished by the rocking of a detent 286 (Fig. 8) pivotally mounted at 286a on the frame. It is rocked by the energizing of solenoid 279 upon the receipt of an elevator operating signal in the manner described. The right arm of detent 286 is connected with the armature 279a of the solenoid through a link 279b. It is normally urged into active position by a spring 279c. When this detent 286 is rocked in a counterclockwise

direction its free end is disengaged from the arm 287 secured to shaft 15. This permits a slight angular movement of the shaft and serves to carry the arm 287 over the top of the detent 286. The shaft, however, is stopped 5 against further rotation at this time by a detent 346 (Fig. 11) extending radially from a crank disc 347 secured to the shaft outside of the housing. Detent 346 engages a shoulder on a pawl 348 pivotally mounted on an arm 349 which is in turn pivotally mounted at 350 on the 10 frame. The limited rotation of shaft 15 serves to move the pawl 348 bodily upward to engage a finger 351 with a tooth on a ratchet wheel 352. The latter, as explained in the prior Ackell patent, normally rotates with the shaft 14. It has a screw threaded mounting on a stud 14a forming an extension of shaft 14 and it is spring urged in a counterclockwise direction (Fig. 11) so that normally a projection 352a (Fig. 10) is held against a stop shoulder 352b carried by an adjustable cap 352d on extension 14a of shaft 14. However, when the ratchet 15 is held against turning by the pawl 348, it will advance axially along the screw threaded extension 14a until the opposite side of stop 352a engages a shoulder 352c on a collar secured to the extension 14a adjacent its inner end. The cap 352d may be turned in relation 20 to the extension 14a to vary the number of revolutions of shaft 14 required to shift the ratchet 352 to engage the projection 352a with shoulder 352c. When it reaches this position the further rotation of shaft 14 will serve to drive the ratchet positively and cause it to rock the pawl 348 about its pivotal support on the arm 349 and thus disengage the tooth of the pawl from the detent 346. This will permit the shaft 15 to complete its first 25 half revolution, in the course of which the elevator of link 353 (Fig. 11) connected at one end with a crank pin on the disc 347 and at its other end with the elevator operating linkage in the manner disclosed in said prior Ackell patent. At the end of a half revolution of shaft 15 it is held by the cooperation of arm 296 with the detent 286. The shaft 15 is thus held against further turning 30 until the solenoid 279 is energized again by the closing of the switch 297 (Fig. 1d) upon the return of the cross delivery mechanism of the line casting machine to its normal position. When the solenoid is thus energized the shaft completes its single revolution, at which time arm 287 again engages detent 286. During the second half revolution of shaft 15 the elevator is restored to its lower position.

Means are provided for bringing about manual release 50 of the shaft 15 whenever desired. A key lever 354 is provided for this purpose, this being carried by a rock shaft 355 mounted on the frame. A clip 356 is preferably provided to limit the extent of downward movement of the key lever. Within the housing of the unit the shaft 355 carries a spring arm 357 (Fig. 8) which is arranged to cooperate with a plunger actuated switch 358. This switch is schematically indicated in Fig. 1e. When this switch is operated a circuit will be completed from the line 26 through line 27, line 277, the solenoid 279, line 299a and line 359 to and through the switch 358, then up to line 60 extending from the negative side of the power line. It will be understood that the key 354 will be operated and released to bring about the operation of the mechanical time delay means and the operation of shaft 15 through a half revolution. When the cross delivery mechanism has been restored to its normal position the closing of the switch 297 will energize solenoid 279 in the manner described previously to bring about the return of the elevator.

The arrangement and mode of mounting of the various control cams on the shafts 14 and 15 described in relation to the circuit diagram are indicated in Figs. 7, 12, and 13. These cams are formed of a suitable insulating material and are mounted in appropriately spaced relation on the shafts 14 and 15. The relationship between

cams 288, 289, and 298, on shaft 15 and the cooperating switches 50, 290, and 299 is shown in Fig. 12 and partly in Fig. 7. In Fig. 13 there is shown the cam II mounted on the shaft 14 and the cooperating switches 71 and 92 suitably mounted in the housing of the cam shaft assembly in positions 180° apart in relation to the actuating bump on the cam. The remaining cams and switches identified with shaft 14 are mounted in similar fashion, all of the switches being carried by but insulated from a common supporting bar. The relationship between cam 298 on shaft 15 and the cam II on shaft 14 is also indicated in Fig. 13. It should be noted that the two shafts are rotated in opposite directions, although in Fig. 1e they are indicated, for convenience, as being rotated in the same direction.

Fuses 278 and 291a, which protect certain of the circuits within the unit, are shown in Figs. 11 and 12. These are inserted in suitable sockets provided at the bottom of the housing for the cam shaft unit.

It will be understood that wires or cables are provided within the unit for interconnecting the various electrical devices of the cam shaft unit in accordance with the circuit diagram. These wires or cables extend to two Jones plug elements carried by the housing for reception of the mating Jones plug elements 28 and 37 shown in the circuit diagram, Figs. 1e and 1d, respectively.

Another feature of the invention is disclosed in Figs. 17 to 25 inclusive. This involves the provision of a readily connectable and disconnectable relay unit 360 in proper relation to a key actuating solenoid assembly 361. The solenoids are mounted as a bank in a suitable unit, of the character illustrated in the above mentioned Ackell patents, directly over the keys of the line casting machine. The relay unit 360 embodies the relays 12, 17, 18, etc. and the various switches controlled by these relays. It also carries the requisite wiring system to provide the circuits disclosed in the wiring diagram. Relay unit 360 is connected with the solenoid unit 361 by means of a plurality of bracket elements 362 secured to the bottom of unit 360 and cooperating bracket elements 363 secured to the unit 361. As best shown in Figs. 24 and 25, the elements 362 are provided with downwardly extending tongues 362a adapted for insertion in slots 363a of the elements 363. This serves to retain the lower edge of unit 360 in proper relation to unit 361.

For retaining the upper portion of unit 360 in proper position a hood-like member 364 is provided, this having a handle 365. The hood member, as will be explained, is arranged to be readily applied to and removed from the two units when they are properly assembled. When the hood member is applied it will serve to squeeze together certain contact elements which interconnect the portions of the various circuits embodied in the relay unit 360 with the continuation of those circuits embodied in the solenoid unit 361. The contact elements of the solenoid unit are indicated at 366. These are embedded in a strip 367 of sponge rubber or the like attached to a plate 368 preferably formed of Bakelite or similar insulating material. A contact 366 is provided for each of the solenoids in the unit 361. To each of the contacts 366 there is connected a separate wire 366a from the wiring system within the solenoid unit. The mounting of the contact elements 366 is such that they may be forced yieldingly inwardly against the resilient action of the rubber strip 367. Unit 360 is provided with a plate 369, formed of Bakelite or the like, carrying a plurality of contact elements 370 corresponding in number with the contact elements 366. To each of the contact elements 370 a wire 370a is connected from the system of wiring within the unit 360.

The hood member 364 is provided with downwardly extending supports at suitably spaced points arranged to carry rollers 371 and 372 (Figs. 18, 19, 20, and 21). These rollers are arranged to slide downwardly along the innermost faces of the plates 368 and 369 as the

hood is applied over the junction of the two units and serves to squeeze the plates 368 and 369 toward each other. This provides a firm engagement between the contacts 366 and cooperating contacts 370 and forces the contacts 366 slightly into the supporting rubber strip 367. In applying the hood member 364 in the manner explained, the rollers 371 pass downwardly through openings 373 in the unit 361, while the rollers 372 pass through openings 374 in the top of unit 360. At each end of the hood member 364 a downwardly extending skirt 364a is provided, this being notched in its underedge to fit over the shanks of screws 375 carried by the units 360 and 361. Upon tightening of these screws the assembly of the two units is firmly maintained.

The foregoing arrangement is such that if any difficulty is encountered in the operation of the relay unit 360 this may be readily detached and a new unit substituted for it so that the control of the line casting machine will be interrupted for only a brief interval. One or more spare relay units 360 may be provided for each line casting machine. It will be understood that the relay unit 360 is connected into the rest of the circuit shown in the circuit diagram through one of the Jones plugs 31 or through the plug 266, depending upon whether the comparing relays are or are not in the circuits of the control system.

While an illustrative and preferred embodiment of the improved control system has been disclosed in considerable detail, it should be understood that various changes may be made in the construction and arrangement of the various parts within the scope of the appended claims.

What is claimed is:

1. In a punched tape control system for a line casting machine a tape feeding and analyzing device, a first group of relays selectively energized in accordance with successive combinations of perforations in a tape advanced through said device, a second group of relays, means operated periodically to energize relays in said second group selectively to correspond with the energized relays in said first group, a third group of relays, circuits connecting said third group of relays with said second group to energize relays in said third group corresponding with relays energized in said second group, said line casting machine having a plurality of key actuated mechanisms for controlling the operation of the machine, a plurality of solenoids each arranged to operate one of said key actuated mechanisms, electrical connections controlled by said third group of relays for delivering current to said solenoids for selectively operating said mechanisms, switch means in said electrical connections for periodically causing the delivery of current to said solenoids, timing means for determining the frequency of operation of said switch means, and means for controlling said timing means to vary the frequency of said operation of said switch means in accordance with the nature of the series of perforations in said tape.

2. In a punched tape control system for a line casting machine a tape feeding and analyzing device, a first group of relays selectively energized in accordance with successive combinations of perforations in a tape advanced through said device, a second group of relays, means operated periodically to energize relays in said second group selectively to correspond with the energized relays in said first group, a third group of relays, circuits connecting said third group of relays with said second group to energize relays in said third group corresponding with relays energized in said second group, said line casting machine having a plurality of key actuated mechanisms for controlling the operation of the machine, a plurality of solenoids each arranged to operate one of said key actuated mechanisms, electrical connections controlled by said third group of relays for delivering current to said solenoids for selectively operating said mechanisms, switch means in said electrical connections for periodically causing the delivery of current to said solenoids, timing means for determining the frequency of operation of said switch means, and means for controlling said timing means to vary the frequency of said operation of said switch means in accordance with the nature of the series of perforations in said tape.

noids, timing means for determining the frequency of operation of said switch means, and means for controlling said timing means to vary the frequency of said operation of said switch means in accordance with the nature of the series of perforations in said tape, said last mentioned means being arranged to prolong the period between successive operations of said solenoids whenever said tape is provided with duplicate series of perforations in successive portions of said tape.

3. In a punched tape control system for a line casting machine a tape feeding and analyzing device, a first group of relays selectively energized in accordance with successive combinations of perforations in a tape advanced through said device, a second group of relays, means operated periodically to energize relays in said second group selectively to correspond with the energized relays in said first group, a third group of relays, circuits connecting said third group of relays with said second group to energize relays in said third group corresponding with relays energized in said second group, said line casting machine having a plurality of key actuated mechanisms for controlling the operation of the machine, a plurality of solenoids each arranged to operate one of said key actuated mechanisms, electrical connections controlled by said third group of relays for delivering current to said solenoids for selectively operating said mechanisms, switch means in said electrical connections for periodically causing the delivery of current to said solenoids, timing means for determining the frequency of operation of said switch means, and means for controlling said timing means to vary the frequency of said operation of said switch means in accordance with the nature of the series of perforations in said tape, said last mentioned means being arranged to prolong the period between successive operations of said solenoids in response to a predetermined relation between the perforations of a particular series in said tape.

4. In a punched tape control system for a line casting machine having a plurality of key operated solenoids for controlling the operation of said machine and electrically operated means associated with each of said key operated elements for operating the same, a perforated tape feeding and analyzing device, a plurality of groups of relays of like number, a relay in each of said groups being coordinated with like relays of the other of said groups, means for controlling the setting of one of said groups of relays in accordance with successive groups of perforations in said tape, means for transferring the setting of the relays in said one of said groups to those in a second of said groups to effect a corresponding setting of the relays in the two groups of relays, means controlled by the relays of said second group for operating said key operated elements in accordance with the setting of the relays of said second group, said last mentioned means being normally operated at periodic time intervals of predetermined duration, and means controlled by a particular setting of the relays of said second group for varying the duration of said time interval.

5. In a punched tape control system for a line casting machine having a plurality of key operated elements for controlling the operation of said machine and electrically operated means associated with each of said key operated elements for operating the same, a perforated tape feeding and analyzing device, a plurality of groups of relays of like number, a relay in each of said groups being coordinated with like relays of the other of said groups, means for controlling the setting of one of said groups of relays in accordance with successive groups of perforations in said tape, means for transferring the setting of the relays in said one of said groups to those in a second of said groups to effect a corresponding setting of the relays in the two groups of relays, means controlled by the relays of said second group for operating said key operated elements in accordance with the setting of the relays of said second group, said last men-

tioned means being normally operated at periodic time intervals of predetermined duration, and means controlled by corresponding setting of said two groups of relays for varying the duration of said time interval.

5. In a punched tape control system for a line casting machine having a plurality of key operated elements for controlling the operation of said machine and electrically operated means associated with each of said key operated elements for operating the same, a perforated tape feeding and analyzing device, a plurality of groups of relays of like number, a relay in each of said groups being coordinated with like relays of the other of said groups, means for controlling the setting of one of said groups of relays in accordance with successive groups of perforations in said tape, means for transferring the setting of the relays in said one of said groups to those in a second of said groups to effect a corresponding setting of the relays in the two groups of relays, means controlled by the relays of said second group for operating said key operated elements in accordance with the setting of the relays of said second group, said last mentioned means being normally operated at periodic time intervals of predetermined duration, and means controlled by a particular setting of the relays of at least one of said groups for varying the duration of said time interval.

7. In a punched tape control system for a line casting machine having a plurality of key operated elements for controlling the operation of said machine and electrically operated means associated with each of said key operated elements for operating the same, a perforated tape feeding and analyzing device, a plurality of groups of relays of like number, a relay in each of said groups being coordinated with like relays of the other of said groups, means for controlling the setting of one of said groups of relays in accordance with successive groups of perforations in said tape, means for transferring the setting of the relays in said one of said groups to those in a second of said groups to effect a corresponding setting of the relays in the two groups of relays, means controlled by the relays of said second group for operating said key operated elements in accordance with the setting of the relays of said second group, said last mentioned means being normally operated at periodic time intervals of predetermined duration, and means controlled by coincidence of the settings of said first and second of said groups of relays for varying the duration of said time intervals.

8. In a punched tape control system for a line casting machine having a plurality of key operated elements for controlling the operation of said machine and electrically operated means associated with each of said key operated elements for operating the same, a perforated tape feeding and analyzing device, a plurality of groups of relays of like number, a relay in each of said groups being coordinated with like relays of the other of said groups, means for controlling the setting of one of said groups of relays in accordance with successive groups of perforations in said tape, means for transferring the setting of the relays in said one of said groups to those in a second of said groups to effect a corresponding setting of the relays in the two groups of relays, means controlled by the relays of said second group for operating said key operated elements in accordance with the setting of the relays of said second group, said last mentioned means being normally operated at periodic time intervals of predetermined duration, means controlled by coincidence of the settings of said first and second of said groups of relays for varying the duration of said time intervals, and means for rendering said last mentioned means ineffective when at least one of said groups of relays has a predetermined setting.

9. In a punched tape control system for a line casting machine having a plurality of key operated elements for controlling the operation of said machine and electric-

cally operated means associated with each of said key operated elements for operating the same, a perforated tape feeding and analyzing device, a plurality of groups of relays of like number, a relay in each of said groups being coordinated with like relays of the other of said groups, means for controlling the setting of one of said groups of relays in accordance with successive groups of perforations in said tape, means for transferring the setting of the relays in said one of said groups to those in a second of said groups to effect a corresponding setting of the relays in the two groups of relays, means controlled by the relays of said second group for operating said key operated elements in accordance with the setting of the relays of said second group, said last mentioned means being normally operated at periodic time intervals of predetermined duration, and means controlled by coincidence of the settings of said first and second of said groups of relays and independently by a predetermined setting of said second group of relays for varying the duration of said time intervals.

10. In a punched tape control system for a line casting machine having a plurality of key operated elements for controlling the operation of said machine and electrically operated means associated with each of said key operated elements for operating the same, a perforated tape feeding and analyzing device, a plurality of groups of relays of like number, a relay in each of said groups being coordinated with like relays of the other of said groups, means for controlling the setting of one of said groups of relays in accordance with successive groups of perforations in said tape, means for transferring the setting of the relays in said one of said groups to those in a second of said groups to effect a corresponding setting of the relays in the two groups of relays, means controlled by the relays of said second group including a third group of relays arranged to be set to coincide with the setting of said second group of relays for operating said key operated elements in accordance with the setting of the relays of said second group, said last mentioned means being normally operated at periodic time intervals of predetermined duration, and means controlled by a particular setting of the relays of said second group for varying the duration of said time interval.

11. An automatic control system for a line casting machine having matrix storing and releasing means and electrical devices for selectively actuating the matrix releasing means, said system comprising a timing unit having a constantly rotating shaft driven at a predetermined speed, a device for intermittently advancing a punched tape and analyzing successive lines of code perforations therein, electrical circuits controlled by said timing unit for selectively energizing said matrix releasing devices for successively releasing matrices predetermined by the code perforations in said tape, a selected one of said circuits normally being closed by said timing unit to release a matrix upon each revolution of said shaft, and means controlled by the perforations in said tape for rendering said circuits ineffective to release a matrix during one revolution of said shaft and restoring the effectiveness of said circuits for the next revolution of said shaft.

12. An automatic control system for a line casting machine having matrix storing and releasing means and electrical devices for selectively actuating the matrix releasing means, said system comprising a timing unit having a constantly rotating shaft driven at a predetermined speed, a device for intermittently advancing a punched tape and analyzing successive lines of code perforations therein, electrical circuits controlled by said timing unit for selectively energizing said matrix releasing devices for successively releasing matrices predetermined by the code perforations in said tape, a selected one of said circuits normally being closed by said timing unit to release a matrix upon each revolution of said shaft, and means controlled by the perforations in said tape for rendering said circuits ineffective to release a matrix during one revolution of said shaft and restoring the effectiveness of said circuits for the next revolution of said shaft.

tion of said shaft and restoring the effectiveness of said circuits for the next revolution of said shaft, said last mentioned means being responsive to successive lines of perforation in the tape which are identical and identified with the release of matrices.

13. An automatic control system for a line casting machine having matrix storing and releasing means and electrical devices for selectively actuating the matrix releasing means, said system comprising a timing unit having a constantly rotating shaft driven at a predetermined speed, a device for intermittently advancing a punched tape and analyzing successive lines of code perforations therein, electrical circuits controlled by said timing unit for selectively energizing said matrix releasing devices for successively releasing matrices predetermined by the code perforations in said tape, a selected one of said circuits normally being closed by said timing unit to release a matrix upon each revolution of said shaft, and means controlled by the perforations in said tape for rendering said circuits ineffective to release a matrix during one revolution of said shaft and restoring the effectiveness of said circuits for the next revolution of said shaft, said last mentioned means being responsive to a line of perforations identified with a specific type of matrix to be released.

14. An automatic control system for a line casting machine having matrix storing and releasing means and electrical devices for selectively actuating the matrix releasing means, said system comprising a timing unit having a constantly rotating shaft driven at a predetermined speed, a device for intermittently advancing a punched tape and analyzing successive lines of code perforations therein, electrical circuits controlled by said timing unit for selectively energizing said matrix releasing devices for successively releasing matrices predetermined by the code perforations in said tape, a selected one of said circuits normally being closed by said timing unit to release a matrix upon each revolution of said shaft, and means controlled by the perforations in said tape for rendering said circuits ineffective to release a matrix during one revolution of said shaft and restoring the effectiveness of said circuits for the next revolution of said shaft, said last mentioned means being responsive to a line of perforations identified with a specific type of matrix to be released.

15. An automatic control system for a line casting machine having matrix storing and releasing means and electrical devices for selectively actuating the matrix releasing means, said system comprising a timing unit having a constantly rotating shaft driven at a predetermined speed, a device for intermittently advancing a punched tape and analyzing successive lines of code perforations therein, electrical circuits controlled by said timing unit for selectively energizing said matrix releasing devices for successively releasing matrices predetermined by the code perforations in said tape, a selected one of said circuits normally being effective to release a matrix upon each revolution of said shaft, and means controlled by the perforations in said tape for rendering said circuits ineffective to release a matrix during one revolution of said shaft and restoring the effectiveness of said circuits for the next revolution of said shaft, said last mentioned means including a plurality of groups of relays in said circuits each relay of each group being related to a perforation in a particular position across the tape, electrical connections arranged to interconnect the relays of the several groups identified with a perforation in a particular position, electrical circuits controlled by said shaft for periodically energizing the relays of a first of said groups under control of said tape analyzing device, electrical circuits controlled by said shaft for energizing the relays of a second group in accordance with the setting of the relays of said first group; and

an electrical circuit energized under control of said shaft whenever the setting of the relays in said first and second groups coincide to interrupt the circuits through said matrix releasing devices during a revolution of said shaft.

16. An automatic control system for a line casting machine having matrix storing and releasing means and electrical devices for selectively actuating the matrix releasing means, said system comprising a timing unit having a constantly rotating shaft driven at a predetermined speed, a device for intermittently advancing a punched tape and analyzing successive lines of code perforations therein, electrical means and a circuit therefor controlled by said shaft for operating said last mentioned device, electrical circuits controlled by said timing unit for selectively energizing said matrix releasing devices for successively releasing matrices predetermined by the code perforations in said tape, a selected one of said circuits normally being effective to release a matrix upon each revolution of said shaft, and means controlled by the perforations in said tape for rendering said circuits ineffective to release a matrix during one revolution of said shaft and restoring the effectiveness of said circuits for the next revolution of said shaft, said last mentioned means including a plurality of groups of relays in said circuits, each relay of each group being related to a perforation in a particular position across the tape, electrical connections arranged to interconnect the relays of the several groups identified with a perforation in a particular position, electrical circuits controlled by said shaft for periodically energizing the relays of a first of said groups under control of said tape analyzing device, electrical circuits controlled by said shaft for energizing the relays of a second group in accordance with the setting of the relays of said first group, an electrical circuit energized under control of said shaft whenever the setting of the relays in said first and second groups coincide to open a switch common to the circuits through said matrix releasing devices and the circuit through said electrical means for operating the tape feeding and analyzing device, and a circuit in parallel with the opposite sides of said common switch for completing the circuit through said electrical means when the relays of said two groups are both set in accordance with a particular line of code perforations.

17. An automatic control system for a line casting machine having matrix storing and releasing means, electrical devices for selectively actuating the matrix releasing means, means for assembling a line of matrices to be cast and devices for transferring the assembled line to a line casting position, said system comprising a timing unit having a constantly rotating shaft driven at a predetermined speed, a device for intermittently advancing a punched tape and analyzing successive lines of code perforations therein, electrical circuits controlled by said timing unit for selectively energizing said matrix releasing devices for successively releasing matrices predetermined by the code perforations in said tape, a selected one of said circuits normally being effective to release a matrix upon each revolution of said shaft, means controlled by the perforations in said tape for rendering said circuits ineffective to release a matrix during one revolution of said shaft and restoring the effectiveness of said circuits for the next revolution of said shaft, said last mentioned means including a plurality of groups of relays in said circuits, each relay of each group being related to a perforation in a particular position across the tape, electrical connections arranged to interconnect the relays of the several groups identified with a perforation in a particular position, electrical circuits controlled by said shaft for periodically energizing the relays of a first of said groups under control of said tape analyzing device, electrical circuits controlled by said shaft for energizing the relay of a second group in accordance with the setting of the relays of

said first group, and an electrical circuit energized under control of said shaft whenever the setting of the relays in said first and second groups coincide to interrupt the circuits through said matrix releasing devices during a revolution of said shaft, a second shaft in said timing unit arranged to be driven by said first mentioned shaft, means normally preventing rotation of said second shaft, electrical means responsive to a predetermined arrangement of the perforations in a line across the tape for enabling rotation of said second shaft, means connected with said second shaft for operating said devices for transferring an assembled line of matrices to the casting position, and means controlled by said second shaft for disabling the matrix releasing means during operation of said transferring devices.

18. An automatic control system for a line casting machine having matrix storing and releasing means and electrical devices for selectively actuating the matrix releasing means, said system comprising a timing unit having a constantly rotating shaft driven at a predetermined speed, a plurality of cams carried by said shaft and a greater plurality of switches operated periodically by said cams, a device for intermittently advancing a punched tape and analyzing successive lines of code perforations therein, electrical circuits including a switch controlled by a cam on said shaft for selectively energizing said matrix releasing devices for successively releasing matrices predetermined by the code perforations in said tape, a selected one of said circuits normally being effective to release a matrix upon each revolution of said shaft, and means controlled by the perforations in said tape for rendering said circuits ineffective to release a matrix during one revolution of said shaft and restoring the effectiveness of said circuits for the next revolution of said shaft, said last mentioned means including a plurality of groups of relays in said circuits, each relay of each group being related to a perforation in a particular position across the tape, electrical circuits controlled by certain of said switches for periodically energizing selected relays of a first of said groups under control of said tape analyzing device, electrical circuits controlled by other of said switches for energizing the relays of a second group in accordance with the setting of the relays of said first group, and an electrical circuit energized under control of said shaft whenever the setting of the relays in said first and second groups coincide to interrupt the circuits through said matrix releasing devices during a revolution of said shaft.

19. An automatic control system for a line casting machine having matrix storing and releasing means, electrical devices for selectively actuating the matrix releasing means, means for assembling a line of matrices to be cast and devices for transferring the assembled line to a line casting position, said system comprising a timing unit having a constantly rotating shaft driven at a predetermined speed, a device for intermittently advancing a punched tape and analyzing successive lines of code perforations therein, electrical circuits controlled by said timing unit for selectively energizing said matrix releasing devices for successively releasing matrices predetermined by the code perforations in said tape, a selected one of said circuits normally being effective to release a matrix upon each revolution of said shaft, and means controlled by the perforations in said tape for rendering said circuits ineffective to release a matrix during one revolution of said shaft and restoring the effectiveness of said circuits for the next revolution of said shaft, said last mentioned means including a plurality of groups of relays in said circuits each relay of each group being related to a perforation in a particular position across the tape, electrical circuits controlled by said shaft for periodically energizing selected relays of a first of said groups under control of said tape analyzing device and for holding said relays energized during a major portion of a revolution of said shaft, electrical circuits controlled

by said shaft for energizing selected relays of a second group in accordance with the setting of the relays of said first group and for holding said second group of relays energized during a major portion of a revolution of said shaft in different timing relation to the energizing and holding of relays of the first group, and an electrical circuit energized under control of said shaft whenever the setting of the relays in said first and second groups coincide to interrupt the circuits through said matrix releasing devices during a revolution of said shaft.

20. An automatic control system for a line casting machine having matrix storing and releasing means, a plurality of electrical devices for selectively actuating the matrix releasing means, a different one of said devices being identified with each different form of matrix to be released, means including a rectifier connected with each of said electrical devices and a plurality of relays arranged to operate a greater plurality of switch arms for selectively providing an electrical circuit through any one of said electrical devices, the number of said switch arms being substantially less than half the number of said electrical devices, means for advancing and analyzing a perforated tape, electrical circuits controlled by the tape analyzing means for selectively energizing said relays in accordance with the perforations in said tape, timing means, and means controlled by said timing means for periodically energizing the electrical device selected by said relays and for operating said tape advancing means to advance the tape.

21. In an automatic control system for a line casting machine having matrix storing and releasing means, a plurality of solenoids for selectively operating said matrix releasing means, each of said solenoids being related to a particular matrix releasing means for operating the same, a plurality of circuits arranged to energize selectively any one of said solenoids, said circuits including a rectifier in series with each of said solenoids and a plurality of relays, said relays having switches arranged upon selective operation of the relays in accordance with a predetermined code system to provide a circuit through a selected one of said solenoids and its connected rectifier, means for advancing and analyzing a perforated tape having successive lines of coded perforations therein, electrical circuits controlled by said tape analyzing means for selectively operating said relays in accordance with the perforations in said tape, and a periodically operated switch common to the circuits through all of said solenoids for closing the circuit through the solenoid selected by the operation of said relays to thereby operate the related matrix releasing means.

22. In an automatic control system for a line casting machine having matrix storing and releasing means, electrical devices for operating said matrix releasing means, one of said devices being provided for each different type of matrix to be released, a plurality of electrical circuits including a power source arranged to energize selectively any one of said devices, and means for selecting the circuit to be energized which comprises means for advancing and analyzing a tape having successive lines of perforations in accordance with a predetermined code system, a control unit having a shaft arranged to be revolved at a predetermined speed, electrical means controlled by said shaft for normally operating said tape advancing and analyzing means upon each revolution of the shaft, a first information storing means controlled by said tape analyzing means arranged to receive and store successive items of information represented by lines of perforations in the tape, a second information storing means controlled by said first information storing means arranged to receive and store said successive items of information, said second storing means being arranged to select said circuit to be energized, means for comparing the information stored in said first and second storing means derived from successive lines of perforations in said tape, and means respon-

sive to such comparison of the same information derived from successive lines of perforations in the tape for disabling said tape advancing and analyzing means during a revolution of said shaft.

23. In an automatic control system for a line casting machine having matrix storing and releasing means, electrical devices for operating said matrix releasing means, one of said devices being provided for each different type of matrix to be released, a plurality of electrical circuits including a power source arranged to energize selectively any one of said devices, and means for selecting the circuit to be energized which comprises means for advancing and analyzing a tape having successive lines of perforations in accordance with a predetermined code system, a control unit having a shaft arranged to be revolved at a predetermined speed, electrical means controlled by said shaft for normally operating said tape advancing and analyzing means upon each revolution of the shaft, information storing means controlled by said tape analyzing means arranged to receive and store at least two successive items of information represented by lines of perforations in the tape, said storing means being arranged to control the selection of the circuit of said plurality of circuits to be energized, means for comparing the information stored in said storing means derived from successive lines of perforations in said tape, and means for preventing the closing of a circuit through the selected circuit during a revolution of said shaft when said comparing means finds the same information represented by successive lines of perforation in the tape.

24. In an automatic control system for a line casting machine having matrix storing and releasing means, electrical devices for operating said matrix releasing means, one of said devices being provided for each different type of matrix to be released, a plurality of electrical circuits including a power source arranged to energize selectively any one of said devices, and means for selecting the circuit to be energized which comprises means for advancing and analyzing a tape having successive lines of perforations in accordance with a predetermined code system, a control unit having a shaft arranged to be revolved at a predetermined speed, electrical means controlled by said shaft for normally operating said tape advancing and analyzing means upon each revolution of the shaft, information storing means controlled by said tape analyzing means arranged to receive and store at least two successive items of information represented by lines of perforations in the tape, said storing means being arranged to control the selection of the circuit of said plurality of circuits to be energized, means for comparing the information stored in said storing means derived from successive lines of perforations in said tape, and means for preventing the closing of a circuit through the selected circuit and for preventing the operation of said tape advancing and analyzing means during a revolution of said shaft when said comparing means finds the same information represented by successive lines of perforation in the tape.

25. A control system for a line casting machine having matrix storing and releasing means, keys for operating the releasing means and a solenoid unit positioned over the keys for operating the same, which comprises a relay unit detachably connected with said solenoid unit and arranged to control the selective operation of said solenoids, said solenoid unit and said relay unit each having a plurality of partial circuits and a plurality of rows of contact elements, the contact elements of one of said units being engaged with corresponding contact elements in the other of said units when the units are assembled, thereby interconnecting the plurality of partial circuits in the two units, the contact elements in at least one of said units being resiliently mounted therein and urged toward the contact elements in the other unit, and detachable securing means for said units arranged

to squeeze the contact elements of one against the corresponding contact elements of the other.

26. A control system for a line casting machine having matrix storing and releasing means, keys for operating the releasing means and a solenoid unit positioned over the keys for operating the same, which comprises a relay unit detachably connected with said solenoid unit and arranged to control the selective operation of said solenoids, said solenoid unit and said relay unit each having a plurality of partial circuits and a plurality of rows of contact elements, the contact elements of one of said units being engaged with corresponding contact elements in the other of said units when the units are assembled, thereby interconnecting the plurality of partial circuits in the two units, the contact elements in at least one of said units being resiliently mounted therein and urged toward the contact elements in the other unit, and

5

10

15

detachable securing means for said units arranged to squeeze the contact elements of one against the corresponding contact elements of the other, said detachable securing means comprising disconnectible hinge means adjacent the lower edges of abutting faces of said units and a clamping element for urging together the upper edges of said abutting faces.

UNITED STATES PATENT OFFICE
CERTIFICATE OF CORRECTION

August 5, 1958

Patent No. 2,846,055

Joseph J. Ackell

It is hereby certified that error appears in the printed specification of the above numbered patent requiring correction and that the said Letters Patent should read as corrected below.
